CLAIM

The ornamental design for an interface of an electrical connector, as shown and described.

DESCRIPTION

FIG. 1 is a front, top and right side perspective view showing an interface of an electrical connector in accordance with our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of the environment is for illustrative purposes forms no part of the claimed design. The dash-dot line represent the boundary of the claimed design.
